(57) **CLAIM**

The ornamental design for a mobile phone with a graphical user interface, as shown and described.

DESCRIPTION

The file of this patent contains at least one drawing executed in color. Copies of this patent with color drawings will be provided by the Office upon request and payment of the necessary fee.

FIG. 1 is a front view of a first image in a sequence of a mobile phone with a graphical user interface, showing our new design;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a front view of a seventh image thereof;

FIG. 8 is a front view of an eighth image thereof;

FIG. 9 is a front view of a ninth image thereof;

FIG. 10 is a front view of a first image in a sequence of a second embodiment thereof;

FIG. 11 is a front view of a second image thereof;

FIG. 12 is a front view of a third image thereof;

FIG. 13 is a front view of a fourth image thereof;

FIG. 14 is a front view of a fifth image thereof;

FIG. 15 is a front view of a sixth image thereof;

FIG. 16 is a front view of a seventh image thereof;

FIG. 17 is a front view of an eighth image thereof; and,

FIG. 18 is a front view of a ninth image thereof.

The appearance of the animated image sequentially transitions between the images shown in FIGS. 1 through 9, and FIGS. 10 through 18, respectively. The process or period in which one image transitions to another forms no part of the claimed design.
